(57) CLAIM

The ornamental design for a fastener container, as shown and described.

DESCRIPTION

FIG. 1 is a perspective view of a fastener container showing my new design;

FIG. 2 is a right side view thereof;

FIG. 3 is a left side view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a perspective view thereof illustrating a door in an open position; and,

FIG. 9 is a top plan view of an unfolded blank thereof.

The broken line portion of the figure drawings is included to show unclaimed subject matter only and forms no part of the claimed design.
